(57) **CLAIM**

The ornamental design for a bag, as shown and described.

DESCRIPTION

FIG. 1 is a top elevation view of an embodiment of a bag embodying my new design. The embodiment is in a folded configuration.

FIG. 2 is a rear elevation view of the embodiment of FIG. 1. FIG. 3 is a right side elevation view of the embodiment of FIG. 1.

FIG. 4 is a left side elevation view of the embodiment of FIG. 1.

FIG. 5 is a bottom plan view of the embodiment of FIG. 1.

FIG. 6 is a top plan view of the embodiment of FIG. 1.

FIG. 7 is a top elevation view of the embodiment of FIG. 1

wherein the embodiment is in an unfolded configuration.

FIG. 8 is a top, front, and right side perspective of the embodiment of FIG. 1; and,

FIG. 9 is a rear elevation view of the embodiment of FIG. 1 wherein the embodiment is in the unfolded configuration.

The broken lines showing stitching are for the purposes of illustrating environment and form no part of the claimed design.
